UNITED STATES PATENT OFFICE.

EVAN A. EVANS, OF CHICAGO, ILLINOIS, ASSIGNOR TO CARL ERNST & CO., OF NEW YORK, N. Y., A FIRM.

DESIGN FOR A PICTURE-MOUNT.

40,977.

Specification for Design.

Patented Nov. 8, 1910.

Application filed July 22, 1910. Serial No. 573,357. Term of patent 3½ years.

To all whom it may concern:

Be it known that I, EVAN A. EVANS, a citizen of the United States, residing at Chicago, in the county of Cook and State of Illinois, have invented a new and original and ornamental Design for Picture-Mounts, of which the following is a specification, reference being had to the accompanying drawing, forming a part thereof.

The figure is a front view of a picture mount, showing my new design.

I claim:

The ornamental design for a picture mount, as shown.
